UNITED STATES PATENT OFFICE.

ISAAC H. LEVIN, OF NEW YORK, N. Y., ASSIGNOR TO ELECTROLYTIC OXY-HYDROGEN LABORATORIES, INC., OF NEW YORK, N. Y.

ELECTROLYTIC APPARATUS.

1,360,542.

Specification of Letters Patent. Patented Nov. 30, 1920.

Application filed May 25, 1917, Serial No. 170,853. Renewed April 23, 1920. Serial No. 376,167.

To all whom it may concern:

Be it known that I, ISAAC H. LEVIN, a citizen of the United States, residing at the borough of Manhattan, city, county, and State of New York, have invented certain new and useful Improvements in Electrolytic Apparatus, of which the following is a specification, reference being had therein to the accompanying drawings, which form a part thereof.

My invention relates to electrolytic apparatus and more particularly to apparatus of the uni-polar type for use in the production of oxygen and hydrogen.

In electrolytic apparatus of the type to which my invention relates, oxygen and hydrogen are produced by the decomposition of acidulated water by electrolysis; and the capacity efficiency of the apparatus, or of the volume of gases produced, is dependent in large measure upon the area of the elements of each couple; while the purity of each gas produced is dependent upon a perfect separation of that portion of the apparatus wherein one of the gases is evolved and stored, and of that portion of the apparatus wherein the other gases are evolved and stored. In addition to this complete separation of different portions of each cell from each other, it is necessary to provide a separating diaphragm which will permit the flow of the electric current therethrough while preventing the seepage of gas from one compartment to the other. It is also highly desirable to maintain the pressures on opposite sides of this diaphragm as nearly uniform as possible so as to minimize any tendency toward the seepage of the gas through the diaphragm with resultant impurity in one of the gases produced.

In apparatus of this type, the tank forms one of the electrodes and the cover for this tank is utilized for supporting the other electrode and the separating diaphragm. It is therefore essential to not only insulate the tank from the cover, but also to insulate the other electrode from the cover in a manner to prevent generation of gases by the current going from the cover to the electrode supported thereby or vice versa.

By my present invention, I provide electrolytic apparatus of the uni-polar type capable of high capacity efficiency, not only by reason of large surface areas in the electrodes of each cell, but by reason of the possibility

of combining a plurality of such cells in a single compact apparatus having an offtake system common to all of the cells, which system will be so constructed as to minimize any tendency toward electrolytic action in the offtake in a manner to produce both gases therein with resultant impurity in the product. By this construction, the problem of insulation is very much simplified and uniform pressure in the compartments for each gas is assured. Furthermore, I so construct and arrange the partition, or partitions, dividing the upper portion of the apparatus into compartments for different gases as to always keep the diaphragm in its entirety submerged in the electrolyte, thus minimizing any tendency of the seepage of the gas therethrough because of the drying of a portion of this diaphragm.

I also so construct each partition forming the gas chambers, as to permit the electrolyte to flow from adjacent one electrode to adjacent the other, thus not only compensating for difference in pressure within said partition, and within the portion of the tank immediately below the cover, but on the opposite side of the diaphragm, but also facilitating the delivery of the feed water for diluting the electrolyte, to both sides of the diaphragm simultaneously. The means through which the feed water is thus delivered to, and distributed in, the apparatus is so constructed as to cause the feed water to flow through open troughs upon opposite sides of the diaphragm, the flow of the electrolyte through such elongated open trough permitting any gas contained in the electrolyte flowing from one compartment to the other, to be freed and delivered to each compartment in a manner to prevent its being carried into the other compartment with resultant impurities in the product.

In apparatus made in accordance with my invention, when employing a plurality of couples, the tank proper is provided with a dividing partition, or partitions, so arranged as to permit a free circulation of the electrolyte throughout the tank. The partition, or partitions, dividing the tank in the manner above referred to, are of a height to be spaced below the cover sufficiently to form a plurality of electrolyte chambers in the lower part of the tank and one large gas chamber throughout the upper portion of the tank, and are in electrical connection with the tank

so as to be of the same polarity therewith, and thus present an electrode surface completely surrounding each of the inner electrodes.

5 The invention consists in the novel features of construction and combination of parts hereinafter set forth and described, and more particularly pointed out in the claims hereto appended.

10 Referring to the drawings,

Figure 1 is a side view of an apparatus embodying my invention, parts thereof being broken away upon different planes to disclose portions of the interior arrangement

15 thereof;

Fig. 2 is a plan view thereof with a portion thereof broken away;

Fig. 3 is an end view thereof with a portion broken away;

20 Figs. 4, 5 and 6 are fragmentary views showing modified forms of the invention illustrating different ways of forming a gas tight joint between the cover and the tank, and of forming the gas chamber above the 25 inner electrode; and

Fig. 7 is a view of a still further modified form of securing a gas tight joint about the inner electrode.

Like letters refer to like parts throughout 30 the several views.

In the embodiment of the invention shown in the accompanying drawings, *a* indicates the main tank for the electrolyte, which tank constitutes an electrode of one polarity, 35 adapted to coöperate with an electrode, or electrodes, of the opposite polarity, which are suspended within this tank from a cover *b* closing the top of the tank while being supported and insulated therefrom, in a 40 manner to prevent the escape of gases from within the tank, or the inclusion of this cover in the electrical circuit. In the form of the invention shown in Figs. 1 to 3, a gas tight joint between the tank *a* and its 45 cover *b* is formed by means of a trough *a'* extending entirely about the top of said tank into which a flange *b'* pendant from the cover *b*, projects. Said flange *b'* engages blocks *a''*, of insulating material in the bottom of said trough, and the trough is filled, 50 or partially filled, with a fluid which will not conduct the electricity from the tank to said cover, such as oil or distilled water.

The tank *a* is so supported as to be insulated from the ground.

To increase the capacity efficiency of the apparatus, I preferably divide the lower portion thereof into a plurality of electrolytic chambers, said chambers terminating 60 below the top of the tank sufficiently to form a single large upper gas chamber common to all of the lower chambers in which one of the gases evolved will be delivered and accumulate prior to its delivery from one 65 apparatus through its gas offtake system.

In the form of the invention shown, two such lower chambers are employed, these chambers being formed by the partition *c* which terminates below the cover *b* of the tank. The partition *c* is preferably formed integrally with the tank *a*, although, if desired, it may be formed separately therefrom, so long as it is in electrical connection with the tank, in a manner to be of the same polarity therewith. If desired, the partition *c* 70 may have an opening, or openings *c'* at the bottom thereof, to facilitate a free circulation of the electrolyte through both of the lower chambers of the tank.

Suspended from the cover *b* in a manner so to be insulated therefrom, is an inside electrode, or electrodes *d*, the number of these electrodes corresponding to the number of electrolytic chambers formed within the lower portion of the tank *a*. Hence, when 85 a plurality of such electrodes *d* are employed, the current will flow between one surface thereof and the inner wall of the tank *a* and the opposite outer surface thereof and the partition *c*.

90 Each electrode *d* is formed of sheet metal and substantially cup like, being closed at the bottom and sides, with the exception of a plurality of openings therethrough to facilitate the circulation of the electrolyte 95 about and within same. The electrode *d* is elongated materially in one direction, so as to afford a sufficiently large operative area while permitting the use of a comparatively small tank *a*. The tank *a* is also elongated 100 in one direction.

The electrode *d* is supported from the heads *d'*, each having a screw threaded stem *d*² passing through an opening *b*² in the cover *b*, said stems each being held in a fitting *d*³ 105 seating upon a packing gasket *d*⁴ forming a gas tight joint about said stem. The fittings *d*³ are clamped by means of screws *d*⁵, upon said gasket *d*⁴, said screws being insulated from said fittings.

110 To separate the gases evolved as the result of the passing of the electric current between the tank *a* and partition *c*, and the electrode *d*, it is necessary to interpose a gas impervious diaphragm between said electrode *d* and the surface of the other electrode, and also to provide a separate gas chamber into which the gas evolved at the inner electrode *d* flows and accumulates, prior to being drawn from the apparatus 115 through the gas offtake system.

In the accompanying drawings, such a diaphragm, which ordinarily is made of asbestos, is shown at *e*, this diaphragm being cup-shaped and of a size to completely close the electrode *d*.

120 The gas chamber for receiving the gas evolved at the electrode *d* is formed by a partition pendant from the cover, preferably in the form of an inverted trough *f*, said 130

- partition projecting within the tank to an extent to bring the lower edge thereof considerably below the normal level of the electrolyte within the tank *a*. The diaphragm *e* 5 is attached in any desired manner to the outer wall of the inverted trough *f*, so that said trough will form a solid barrier between the gas chamber at the top of the tank *a*, and the chamber within said trough, thus 10 preventing any possible seepage of gas from one of said chambers to the other in the event of a temporary differential of pressures of the gases in said chambers. To equalize such pressures, I provide the partitions forming the trough *f* with an opening through which the electrolyte may flow from one side of said diaphragm to the other side thereof, and a diluting fluid, such as distilled water, for the electrolyte may flow on 15 opposite sides of said diaphragm.
- In the form of the invention shown in Figs. 1 to 4 and 7, the trough *f* is made integrally with the cover *b*, while in the form of the invention shown in Figs. 5 and 6, this 20 trough is made separately therefrom and is connected thereto in a particular manner, which will be referred to hereinafter.
- The trough *f* constitutes a partition forming a gas tight chamber within the upper portion of the tank *a*, which partition has 25 therein an opening through which the electrolyte may pass from one side of the diaphragm to the other side thereof, said opening being below, but adjacent, the normal level of the electrolyte, and means being provided whereby the escape of gas bubbles therethrough is prevented. In the form of the invention shown, this means comprises a trough *g* supported from the lower edge 30 of the trough *f*, the side walls at one end thereof merging into the wall of said trough *f* and at the other end thereof having openings toward the bottom of the trough, and the side walls of said trough *g* being arranged upon opposite sides of a portion of 35 said trough *f*. Diluting fluid may be delivered to the apparatus through said trough *g*. The side walls of said trough extend above the normal level of the electrolyte in 40 the tank *a* thus permitting gas to escape from the top of said trough at opposite sides of the wall of the trough *f* in a manner to minimize likelihood of bubbles being carried through the openings *f* from one side of 45 the diaphragm to the other, the openings at the bottom of said trough *g* limiting the flow of the electrolyte from the tank *a* into the trough *g* to a point below the normal level of the electrolyte.
- 50 The opening *f* is in a partition *f* extending from one wall of the trough *f* to the other and is of substantially the same dimensions as an opening *f* in the side wall of said trough *f*. The two chambers *f*-*f* formed by the partition *f* are closed at the 55 bottom by the trough *g* and the openings *f*-*f* are so positioned as to be below the normal level of the electrolyte in the tank *a*. Said chambers are in communication with each other through the opening or port *f*, 60 one of said chambers *f* being in direct communication with the trough *g* upon one side of the wall of the trough *f*, and the other chamber being in communication through the opening or port *f* with the portion of 65 the trough *g* upon the other side of said wall. Said trough *g* is closed at the bottom.
- Discharging into one of the chambers *f*-*f* is a feed cup *h*, said cup, when a plurality of troughs *f* are employed with a 70 single apparatus, communicating with all of said troughs through a duct *i* carried by the cover *b* and communicating with the chamber *f* of said troughs respectively.
- Leading from the gas chamber formed at 75 the top of the tank *a* is a gas offtake system *j* including therein an ordinary lantern *j* and communicating with the trough *f* is the gas offtake system *k* including therein a lantern *k*, the construction and operation of 80 said lanterns being old and well known in this art. When a plurality of troughs *f* are employed in a single apparatus, this offtake system includes therein a duct *l* extending from the upper portion of one trough *f* to 85 the upper portion of the other trough or troughs *f*. Associated with said lanterns is an ordinary fluid level and pressure regulator *m*.
- In electrical connection with the tank *a* 90 is a terminal wire *n*, while in electrical communication with the stems *d* of the electrodes *d* is the other terminal wire *o* of said circuit. The direction of the flow of the current in apparatus of this character is immaterial, although, ordinarily the terminal *o* will be positive and the terminal *n* will be negative, because of the relatively greater capacity of the gas chamber at the top of 95 the tank *a* as compared with the capacity of 100 the other gas chambers formed by the troughs *f*.
- In the form of the invention shown in Fig. 4, the construction is as heretofore described with the exception that instead of 105 using the hydraulic joint *a*-*a*-*b*, between the tank *a* and the cover *b*, I employ a compressible gasket *p* between the top of the tank and said cover, said cover being secured in place and said gasket compacted, 110 by means of a plurality of bolts *p* properly insulated from said cover *b*.
- In the form of the invention shown in Fig. 5, the construction is the same as in Fig. 4 with the exception that instead of 115 forming the troughs *f*-*g* integrally with the cover *b*, I make them independently of said cover and bolt them to the cover by means of a continuous flange *q* overhanging 120 the top of the cover and secured in place 125

4
by means of bolts q' . A suitable packing g^2 is used to form a gas tight joint about said flange.

In the form of the invention shown in Fig. 6, the construction is the same as that shown in Fig. 4, with the exception that instead of forming the troughs $f-g$ integrally with the cover b , I form these troughs separately from said cover and suspend them by means of insulated blocks r from the electrode stems d^2 .

In the form of the invention shown in Fig. 7, I employ a trough s corresponding in functionings with the trough g which 15 closes the entire lower end of the trough f being supported from this trough in any desired manner by means of the rivets s' . The bottom of the trough s is spaced away from the lower end of the wall of the trough f so as to permit the circulation of the electrolyte from one side of said trough to the other.

The operation of the herein described apparatus is substantially as follows:—
25 The tank a is charged with electrolyte, ordinarily a caustic soda, or a potash, solution, the electrodes d and their associated diaphragms being assembled in relation to the cover b , before placing this cover in 30 position upon the tank a . When the partition is assembled in this manner, with one inner electrode d in each of the compartments formed toward the bottom of the tank a , the water level will be substantially as 35 indicated in Fig. 2 of the drawings, and the lower end of the trough f and the lower portion of the trough g will be immersed in the electrolyte in the tank, extending to a point sufficiently below, yet adjacent the normal 40 level of, the electrolyte to preserve this condition notwithstanding fluctuations from this normal level upon opposite sides of the diaphragm, due to varying conditions in the gas collecting chamber at the top of the 45 tank a and within the trough or troughs f .

The tank a and the electrodes d need be 50 of no especial polarity such being arbitrarily determined by the control of the direction of the flow of the current. Ordinarily, the positive terminal of the circuit will be connected with the electrodes d , and the negative terminal with the tank a , for the reasons above stated. Under this condition, 55 the decomposition of the electrolyte within the tank will result in oxygen being evolved adjacent the electrodes d and hydrogen being evolved adjacent the wall of the tank a . The diaphragm e being entirely submerged in the electrolyte of the tank a , will permit 60 the flow of the electric current therethrough but so long as the pressure upon the opposite sides of the diaphragm is uniform, will prevent the seepage of the gas therethrough.

As the gas is evolved adjacent the electrodes d , it will accumulate in the form of

bubbles upon said electrode, and will eventually break away from the electrode and rise to the surface of the electrolyte and be released within the trough f . The same condition will prevail as to hydrogen which 70 will be evolved at the tank a and the partition e therein.

The gas which accumulates within the trough or troughs f will flow therefrom through the offtake pipe j and lantern j' 75 to a gasometer, or to some point of consumption or storage, and the gas accumulating in the upper portion of the tank a about said trough or troughs f will flow through the offtake pipe k and lantern k' in the same 80 manner.

The seal at the edge of the tank a will prevent the escape of gases from said tank to atmosphere, while the gas impervious nature of the partition forming the trough f , particularly as to that portion above the normal level of the electrolyte, will prevent the escape of gas from said trough.

While in operation, the fresh electrolyte or distilled water, will be simultaneously delivered upon both sides of the diaphragm e from the feed cup h , duct i and the trough or troughs g . As the water from the duct i , enters the chamber f^4 , it flows therefrom through the openings f' and f^3 to the opposite side of the wall of the trough f , from whence it goes into the tank a either adjacent the inner or the outer side of the diaphragm e . The openings $f'-f^3$ being located below the normal level of the electrolyte in the tank, the flow of gas from one side of the diaphragm to the other is prevented.

The manner of mounting the cover b upon the tank a prevents said cover, or the parts 105 carried thereby, from being included in the electrical current in evolving the different gases, thus preventing the evolution of gas adjacent the metal surfaces of said cover, or the parts carried thereby.

In the event of the development of a differential of pressures upon opposite sides of the diaphragm, the electrolyte will flow from one side of the daphragm, through the trough g , and the opening f^3 to the chamber f^4 , and from this chamber to the port or opening f' , chamber f^5 and into the troughs g upon the other side of the trough f and said diaphragm, thus preventing this tendency toward the development of differential of 115 pressures, resulting in such unequal pressures upon opposite sides of the diaphragm as will tend to break the fluid seal within the trough g or cause the seepage of gases through the diaphragm with resultant im- 120 purities in the product.

As the electrolyte thus flows from one side of the diaphragm to the other through the trough g and an opening through the partition forming the trough f , (and this flow 130

- may be in either direction), it will of necessity traverse a considerable length of trough open at the top and the movement of the electrolyte, will have the effect of releasing 5 any gas bubbles which may be contained therein, so that the gas will be freed and escape from the top of this trough into the gas chamber designated to receive that particular gas.
- 10 An apparatus made in accordance with my invention, possesses the advantages that a large volume capacity may be secured with a small number of parts, and that the insulating problem is very much simplified.
- 15 Furthermore, likelihood of the presence of impurities in the gases due to varying pressures in the gas chambers of the apparatus is practically eliminated or minimized.
- It is not my intention to limit the invention 20 to the precise details of construction shown in the accompanying drawings, it being apparent that such may be varied without departing from the spirit and scope of the invention.
- 25 Having described the invention, what I claim as new and desire to have protected by Letters Patent, is:—
1. An electrolytic apparatus embodying therein a tank adapted to contain electrolyte, a closure therefor, means forming a gas 30 tight joint between said tank and said closure, a partition carried by said closure and projecting within said tank to a point below the normal level of the electrolyte therein, whereby two non-communicating gas chambers are formed in the upper part of said tank, an inner electrode mounted in said tank, a diaphragm carried by said partition between said electrode and said tank, said 35 partition having an opening therethrough above the bottom thereof and adjacent, but below the normal level of the electrolyte in said tank, whereby electrolyte is permitted to flow from one side of said diaphragm to the other, gas offtake systems leading from said gas chambers respectively, and means including said tank and said inner electrode in an electric circuit.
  2. An electrolytic apparatus embodying 40 therein a tank adapted to contain electrolyte, a closure therefor, means forming a gas tight joint between said tank and said closure, a partition carried by said closure and projecting within said tank to a point below the normal level of the electrolyte therein, whereby two non-communicating gas chambers are formed in the upper part of said tank, an inner electrode mounted in said tank, a diaphragm carried by said partition between said electrode and said tank, said 45 partition having an opening therethrough above the bottom thereof and adjacent, but below the normal level of the electrolyte in said tank, whereby electrolyte is permitted to flow from one side of said diaphragm to the other, gas offtake systems leading from said gas chambers respectively, and means including said tank and said inner electrode in an electric circuit.
  3. An electrolytic apparatus embodying 50 therein a tank adapted to contain electrolyte, a closure therefor, means forming a gas tight joint between said tank and said closure, a partition carried by said closure and projecting within said tank to a point below the normal level of the electrolyte therein, whereby two non-communicating gas chambers are formed in the upper part of said tank, an inner electrode mounted in said tank, a diaphragm carried by said partition between said electrode and said tank, said 55 partition having an opening therethrough above the bottom thereof and adjacent, but below the normal level of the electrolyte in said tank, whereby electrolyte is permitted to flow from one side of said diaphragm to the other, gas offtake systems leading from said gas chambers respectively, and means including said tank and said inner electrode in an electric circuit.
  4. An electrolytic apparatus embodying 60 therein a tank adapted to contain electrolyte, a closure therefor, means forming a gas tight joint between said tank and said closure, a partition carried by said closure and projecting within said tank to a point below the normal level of the electrolyte in said tank, whereby electrolyte is permitted to flow from one side of said diaphragm to the other, gas offtake systems leading from said gas chambers respectively, and means including said tank and said inner electrode in an electric circuit.
  5. An electrolytic apparatus embodying 65 therein a tank adapted to contain electrolyte, a closure therefor, means forming a gas tight joint between said tank and said closure, a partition carried by said closure and projecting within said tank to a point below the normal level of the electrolyte therein whereby two non-communicating 70 gas chambers are formed in the upper part of said tank, an inner electrode mounted in said tank, a diaphragm carried by said partition between said electrode and said tank, said partition having an opening therethrough above the bottom thereof and adjacent, but below the normal level of the electrolyte in said tank, whereby electrolyte is permitted to flow from one side of said diaphragm to the other, gas offtake systems leading from said gas chambers respectively, and means including said tank and said inner electrode in an electric circuit.

- ing gas chambers are formed in the upper part of said tank, an inner electrode mounted in said tank, a cup-shaped diaphragm carried by said trough and inclosing said 5 inner electrode, the wall of said trough having an opening therethrough above the bottom thereof and adjacent, but below the normal level of the electrolyte in said tank, whereby electrolyte is permitted to flow 10 from one side of said diaphragm to the other, an elongated trough inclosing the lower edge of said inverted trough, said last named trough opening upwardly upon opposite sides of said inverted trough into 15 said gas chambers respectively and having openings through the side walls thereof communicating with said tank upon opposite sides of said diaphragm, gas offtake systems leading from said gas chambers respectively, and means including said tank and 20 said inner electrode in an electric circuit.
6. An electrolytic apparatus embodying therein a tank adapted to contain electrolyte, a closure therefor, means forming a gas tight joint between said tank and said closure, an inverted trough carried by said closure and projecting within said tank to a point below the normal level of the electrolyte therein, whereby two non-communicating gas chambers are formed in the upper 25 part of said tank, a cup-shaped inner electrode having openings therethrough mounted in said tank, an elongated trough the side walls of which merge into the side walls of said inverted trough, the top of said elongated trough being open throughout a portion thereof and having one side thereof closed adjacent the point where one of said walls merges into the wall of said inverted trough, the other end of said trough discharging into said tank upon opposite sides of the wall of said inverted trough, a partition in said inverted trough forming two chambers and the walls of said inverted trough each having an opening therethrough, whereby feed water for diluting the electrolyte and the electrolyte may flow from one of said chambers into said elongated trough on one side of the wall of said inverted trough, and said other chamber and the portion of said elongated trough on the other side of said wall, a cup-shaped diaphragm carried by said inverted trough and inclosing said inner electrode, gas offtake systems leading from said gas chambers respectively, and means including said tank and said inner electrode in an electric circuit. 70
7. An electrolytic apparatus embodying therein a tank adapted to contain electrolyte, a closure therefor, means forming a gas tight joint between said tank and said closure, a plurality of inner electrodes mounted in said tank, a diaphragm disposed between each of said inner electrodes and said tank, an electro-conductive body electrically connected with said tank and positioned between succeeding inner electrodes, a plurality of partitions adjacent the top of said tank whereby a chamber is formed at the top of said tank, and a chamber is formed above each of said inner electrodes, said chambers being non-communicating, and each of said partitions having an opening therethrough above the bottom thereof and adjacent, but below the normal level of the electrolyte in said tank, whereby electrolyte is permitted to flow from one side of each of said diaphragms to the other side thereof, a gas offtake system communicating with the gas chamber at the top of said tank, a gas offtake system communicating with all of the chambers above said inner electrodes, and means including said tank and all of said inner electrodes in an electric circuit. 75
8. An electrolytic apparatus embodying therein a tank adapted to contain electrolyte, a closure therefor, means forming a gas tight joint between said tank and said closure, a plurality of electrolyte chambers, said partition having an opening therethrough, an inner electrode positioned in each of said electrolyte chambers, a diaphragm inclosing each of said inner elec- 80
9. An electrolytic apparatus embodying therein a tank adapted to contain electrolyte, a closure therefor, means forming a gas tight joint between said tank and said closure, a partition dividing the lower portion of said tank into a plurality of electrolyte chambers, said partition having an opening therethrough, an inner electrode positioned in each of said electrolyte chambers, a diaphragm inclosing each of said inner elec- 85
10. An electrolytic apparatus embodying therein a tank adapted to contain electrolyte, a closure therefor, means forming a gas tight joint between said tank and said closure, a plurality of electrolyte chambers, said partition having an opening therethrough, an inner electrode positioned in each of said electrolyte chambers, a diaphragm inclosing each of said inner elec- 90
11. An electrolytic apparatus embodying therein a tank adapted to contain electrolyte, a closure therefor, means forming a gas tight joint between said tank and said closure, a plurality of electrolyte chambers, said partition having an opening therethrough, an inner electrode positioned in each of said electrolyte chambers, a diaphragm inclosing each of said inner elec- 95
12. An electrolytic apparatus embodying therein a tank adapted to contain electrolyte, a closure therefor, means forming a gas tight joint between said tank and said closure, a plurality of electrolyte chambers, said partition having an opening therethrough, an inner electrode positioned in each of said electrolyte chambers, a diaphragm inclosing each of said inner elec- 100
13. An electrolytic apparatus embodying therein a tank adapted to contain electrolyte, a closure therefor, means forming a gas tight joint between said tank and said closure, a plurality of electrolyte chambers, said partition having an opening therethrough, an inner electrode positioned in each of said electrolyte chambers, a diaphragm inclosing each of said inner elec- 105
14. An electrolytic apparatus embodying therein a tank adapted to contain electrolyte, a closure therefor, means forming a gas tight joint between said tank and said closure, a plurality of electrolyte chambers, said partition having an opening therethrough, an inner electrode positioned in each of said electrolyte chambers, a diaphragm inclosing each of said inner elec- 110
15. An electrolytic apparatus embodying therein a tank adapted to contain electrolyte, a closure therefor, means forming a gas tight joint between said tank and said closure, a plurality of electrolyte chambers, said partition having an opening therethrough, an inner electrode positioned in each of said electrolyte chambers, a diaphragm inclosing each of said inner elec- 115
16. An electrolytic apparatus embodying therein a tank adapted to contain electrolyte, a closure therefor, means forming a gas tight joint between said tank and said closure, a plurality of electrolyte chambers, said partition having an opening therethrough, an inner electrode positioned in each of said electrolyte chambers, a diaphragm inclosing each of said inner elec- 120
17. An electrolytic apparatus embodying therein a tank adapted to contain electrolyte, a closure therefor, means forming a gas tight joint between said tank and said closure, a plurality of electrolyte chambers, said partition having an opening therethrough, an inner electrode positioned in each of said electrolyte chambers, a diaphragm inclosing each of said inner elec- 125
18. An electrolytic apparatus embodying therein a tank adapted to contain electrolyte, a closure therefor, means forming a gas tight joint between said tank and said closure, a plurality of electrolyte chambers, said partition having an opening therethrough, an inner electrode positioned in each of said electrolyte chambers, a diaphragm inclosing each of said inner elec- 130

trodes, a plurality of inverted troughs carried by said closure and projecting within said tank to a point below the normal level of the electrolyte in said tank, each of said troughs having an opening therethrough above the bottom thereof and adjacent, but below the normal level of the electrolyte in said tank whereby electrolyte is permitted to flow from one side of each of said dia-
 phragms to the other side thereof, means preventing gas from flowing through said opening, a gas offtake system communicating with the upper portion of said tank without said troughs, a gas offtake system commu-
 nicating with all of said inverted troughs, and means including said tank and all of said inner electrodes in an electric circuit.

10. An electrolytic apparatus embodying therein a tank adapted to contain electrolyte, a closure therefor, means forming a gas tight joint between said tank and said closure, a partition in electrical connection with, and dividing the lower portion of said tank into a plurality of electrolyte chambers, said par-
 tition having an opening therethrough, an inner electrode positioned in each of said electrolyte chambers, a diaphragm inclosing each of said inner electrodes, a plurality of inverted troughs carried by said closure and
 20 projecting within said tank to a point below the normal level of the electrolyte in said tank, each of said inverted troughs having associated therewith an elongated trough the

side walls of which merge into the side walls of said inverted trough, the top of said elongated trough being open throughout a portion thereof and having one side thereof closed adjacent the point where one of said walls merges into the wall of said inverted trough, the other end of said trough dis-
 35 charging into said tank upon opposite sides of the wall of said inverted trough, a partition in said inverted trough forming two chambers and the walls of said inverted trough each having an opening therethrough, 40 whereby feed water for diluting the electrolyte and the electrolyte may flow from one of said chambers into said elongated trough on one side of the wall of said inverted trough, and said other chamber and the por-
 45 tion of said elongated trough on the other side of said wall, a feed cup, ducts leading therefrom discharging into one of the chambers formed by said partition in said inverted trough, a gas offtake system communi-
 cating with all of said inverted troughs, and means including said tank and all of said inner electrodes in an electric circuit.

50 In witness whereof, I hereunto affix my signature, in the presence of two subscribing 55 witnesses, this 21st day of May, 1917.

ISAAC H. LEVIN.
